(57) CLAIM

The ornamental design for an automobile grill, as shown and described.

DESCRIPTION

FIG. 1 is a top, front and right side perspective view of an automobile grill showing our new design;
FIG. 2 is a front view thereof;
FIG. 3 is a left side view thereof;
FIG. 4 is a right side view thereof; and,
FIG. 5 is a bottom view thereof.

The portions of the automobile shown throughout the drawing views in a deemphasized and faded out half tone form are for environmental and illustrative purposes and form no part of the claimed design.
